UNITED STATES PATENT OFFICE.

JOHN ANDERSON, OF PORTLAND, CONNECTICUT, ASSIGNOR TO THE
ANDERSON COUPLING COMPANY, OF PORTLAND, CONNECTICUT,
A CORPORATION.

WRENCH.

No. 834,242.

Specification of Letters Patent.

Patented Oct. 30, 1906.

Application filed May 7, 1906. Serial No. 315,575.

To all whom it may concern.

Be it known that I, JOHN ANDERSON, a citizen of the United States, residing at Portland, in the county of Middlesex and State of Connecticut, have invented a new and useful Improvement in Wrenches; and I do hereby declare the following, when taken in connection with the accompanying drawings and the letters of reference marked thereon, to be 5
10 a full, clear, and exact description of the same, and which said drawings constitute part of this specification, and represent, in—

Figure 1, a side view of a wrench constructed in accordance with my invention; Fig. 2, a 15 similar view with one side of the handle and link portion removed; Fig. 3, a sectional view on line *a b* of Fig. 1; Fig. 4, an edge view of the jaws detached.

This invention relates to an improvement 20 in wrenches, the object being a simple construction and arrangement of parts permitting a convenient adjustment of the jaws with relation to each other and at various angles with relation to the handle, and the invention 25 consists in the construction and arrangement of parts, as will be hereinafter described, and particularly recited in the claims.

In carrying out my invention I employ a 30 jaw-block 2, having formed with it a fixed jaw 3 and slotted to receive the rack portion 5 of a movable jaw 6, one of the walls of the slot being formed with a longitudinal rib 7, entering a corresponding groove 8, formed in 35 one side of the rack, which at its under edge has teeth 9, which are engaged by a worm-nut 10, mounted upon a pin 11, the nut being exposed on opposite sides by a clearance-opening 12, formed for that purpose in the 40 block 2, so that by the turning of the nut 10 the movable jaw 6 may be moved toward or from the fixed jaw 3. The block 2 is provided at opposite sides with integral studs 13 and 45 14, and one side is thereby pivotally connected to the upper end of the handle portion 15. This handle portion is formed from a strip of metal doubled into substantially U shape and is a little wider at its lower end than at its upper end to form a gripping portion 16. Located within the handle and secured thereto by rivets 17 is a block 18, formed above the grip portion with notches 19.

Preferably and as herein shown the outer

edge of the handle member will be formed 55 with a longitudinal groove or corrugation 20, which strengthens or reinforces the metal. Secured to the studs 14 is a link 21, formed from metal doubled in the same way as the handle portion 15 and at its lower end inclosing a dog 22, having teeth 23 to engage with the notches 19. The outer edge of this link is also formed with a groove 24 in the same way as is the handle portion 15. Pivoted to the lower end of the link 21 is a yoke 60 25, which surrounds the handle portion and contains a flat spring 26, which rides in the groove 20 and holds the dog 22 in engagement with the block 18, yet yields to permit the yoke to be pressed against the handle portion, so as to throw the dog out of engagement with the block, allowing the link to be moved, and so as to turn the jaw-block at various angles with relation to the handle. This construction permits the jaws to be 65 separated or moved toward each other for various sizes of bolts, and by shifting the engagement of the dog with the block the jaws may be turned at various angles to the handle, as may be required for convenience and 70 operation.

I claim—

1. A wrench comprising a jaw-block having a fixed jaw thereon, a movable jaw sliding in said block, and means for adjusting it 85 toward and from the fixed jaw, a handle portion pivoted to one side of said block and containing a notched block, a link pivoted to the opposite side of said jaw-block and containing a dog at its lower end for engagement 90 with the handle portion, and means for holding them in such engagement, substantially as described.

2. A wrench comprising a jaw-block, said block having a fixed jaw and integrally-formed studs at opposite sides, said block also slotted, a movable jaw arranged in said slot, and means for moving it toward and from the fixed jaw, a handle portion connected with the studs at one side of said 95 block, and a link member connected with the studs at opposite sides of said block, said handle member including a notched block, and the link member a toothed dog to engage therewith, and means for holding said dog 100 and block in engagement, substantially as described.

3. A wrench comprising a jaw-block hav-

ing a fixed jaw thereon, a movable jaw sliding in said block and means for adjusting it toward and from the fixed jaw, a handle portion pivoted to one side of said block, said handle portion formed from sheet metal bent into U shape and formed at its outer edge with a longitudinal groove, a block located between the sides of said handle and having its edge notched, a link also connected with said jaw-block and formed from sheet metal, said link containing a dog adapted to engage with said

notched block, and means for holding said dog in engagement with the notched block, substantially as described.

In testimony whereof I have signed this 15 specification in the presence of two subscribing witnesses.

JOHN ANDERSON.
